(57) **CLAIM**

We claim the ornamental design for a battery-powered speaker for handheld devices, as shown and described.

DESCRIPTION

FIG. 1 is an isometric view of the battery-powered speaker for handheld devices, showing primarily the top, front and right side thereof;

FIG. 2 is an isometric view of the battery-powered speaker for handheld devices, showing primarily the top, front and left side thereof;

FIG. 3 is an isometric view of the battery-powered speaker for handheld devices, showing primarily the bottom, front and left side thereof;

FIG. 4 is an isometric view of the battery-powered speaker for handheld devices, showing primarily the bottom, front and right side thereof;

FIG. 5 is a front elevational view of the battery-powered speaker for handheld devices;

FIG. 6 is a rear elevational view of the battery-powered speaker for handheld devices;

FIG. 7 is a top plan view of the battery-powered speaker for handheld devices;

FIG. 8 is a left-side elevational view of the battery-powered speaker for handheld devices;

FIG. 9 is a bottom plan view of the battery-powered speaker for handheld devices; and,

FIG. 10 is a right-side elevational view of the battery-powered speaker for handheld devices.

A major portion of the battery-powered speaker for handheld devices is shown in broken lines for illustrative purposes only and forms no part of the claimed design.

1 Claim, 8 Drawing Sheets
